(57) **CLAIM**

The ornamental design for an earphone, as shown and described.

DESCRIPTION

FIG. 1 is a perspective view of an earphone showing the new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is another perspective view thereof.

The earphone has a streamline shape body. One end of the body has a slanted surface and an inserting portion extending from the slanted surface for fitting into an ear plug. Another end of the body facing a cable has an arcuate bending portion and outer diameters of the bending portion are gradually decreased in the direction away from the inserting portion.
